STANLEY FISHER, OF EALING, AND WINWOOD PRIDDEY, OF MARYLEBONE, LONDON, ENGLAND.

SPARKING PLUG.

Application filed March 30, 1920. Serial No. 369,899.

To all whom it may concern:

Be it known that we, STANLEY FISHER and WINWOOD PRIDDEY, both subjects of the King of Great Britain, residing, respectively, at 8 Derwent Road, Northfields, Ealing, W. 5, and 53 George Street, Portman Square, Marylebone, W. 1, both in the county of London, England, have invented certain new and useful Improvements in Sparking 10 Plugs, of which the following is a specification.

This invention relates to sparking plugs of the kind having the central portion readily removable from the threaded base 15 or outer portion for the purpose of cleaning and adjusting the sparking points or of substituting a new central portion for an old defective one but held in position with sufficient pressure to maintain a gas-tight 20 joint by means of an adjustable member which is independent of or separate from the removable central portion.

According to the present invention, the adjustable member is formed with a slotted 25 flange and may have interposed between it and the central portion a retaining ring or the like. This ring or the central portion itself is formed with lugs or projections which engage in corresponding slots in the 30 base portion of the plug and the slots in the flange of the adjustable member are formed to correspond with the slots in the base portion of the plug. When these slots are caused to coincide or register, the central 35 portion consisting of the electrodes and insulator, together with the retaining ring when such is employed may be removed from or inserted into the base portion of the plug as a separate self-contained unit without 40 detaching the adjustable member. The latter may be in the form of a cap connected to the base portion of the plug by screw threads or any other suitable joint. When the removable central portion is inserted in 45 place, a partial turn of the cap causes the flange of the latter to press downwards upon the retaining ring and exert pressure on the central portion for compressing a suitably arranged washer or washers and making 50 a gas-tight joint. In order to facilitate the removal and re-insertion of the central portion a stop may be provided to ensure that the cap can only be unscrewed until the slots are in register.

In order that the said invention may be 55 clearly understood and readily carried into effect, the same will now be described more fully with reference to the accompanying drawings, in which:—

Figure 1 is an elevation, and 60

Figure 2 a vertical section of the improved sparking plug.

Figure 3 is an elevation partly in section, and 65

Figure 4 a plan of the base portion 65 of the plug that screws into the engine cylinder in the usual manner.

Figure 5 is a vertical section and

Figure 6 a plan of the retaining ring. 70

Figure 7 is a vertical section, and

Figure 8 a plan of the locking member or cap. 75

Figure 9 is an elevation partly in section of the central portion comprising the two electrodes, insulator and retaining ring. 75

Figure 10 shews in vertical section a modified form of the device, in which the negative electrode, instead of being in the form of a thimble, is a plain rod passing through the plug body and fitting tightly 80 into a hole drilled in the part d.

Figure 11 is an elevation of a modified 85 form of sparking plug in which a ring or washer is employed to secure the negative electrode.

Figure 12 is a sectional plan taken on the line 12—12 in Figure 11.

Referring firstly to Figures 1 to 9, a is the central or positive electrode, b the negative or earthed electrode and c the insulator 90 which latter may be of any suitable material such as porcelain, fused quartz, mica and so forth. Both electrodes are preferably tipped with nickel in the neighbourhood of their sparking points. d is the retaining 95 ring which is formed with two diametrically opposite vertical lugs e. These parts, a, b, c and d constitute the removable central portion. The ring d is shown cut away internally to allow the insulator c to have as 100 much cooling surface in contact with the air as possible. f is the base portion of the sparking plug formed with vertical slots g corresponding to the lugs e. The portion f, as usual, has a standard thread at its lower 105 end for screwing into the cylinder of the engine and has the usual hexagonal portion upon which a spanner may be used. h is

the flanged cap. The upper end of the portion *f* is formed with an external square screw-thread *h*, for the reception of a similar thread on the cap *k* which when in place 5 presses upon the ring *d*. This cap *k* has, on opposite sides, the slots *l* which, when in register with the slots *g*, enable the removable central portion with the ring *d* to be withdrawn from the base portion of the 10 plug for inspection or repair. When the central portion is in position in the base portion of the plug, a partial turn of the cap *k* will cause the flange of the latter to press firmly on to the lugs *e* of the ring *d* and 15 compress the washer *n* thus obtaining a gas-tight joint. A washer *m* is also pressed between the ring *d* and the insulator *c*.

o is a stop pin which is mounted in a hole 20 in the base portion *f* and pressed upwards by a spring *p* against an inclined face *o* on the cap *k*. The cap *k* may be unscrewed until it is stopped by the vertical surface or shoulder *r* on the cap coming against the pin *o*. Then the slots *g* are in register with the 25 slots *l* and the central portion may be withdrawn with the ring *d*. Any other suitable form of stop may be used for this purpose.

The central electrode *a* is square in cross-section and fits in a square hole in the insulator *c*. It makes a gas-tight joint at the 30 packing *s* when the nut *t* is screwed down and cannot rotate when the terminal nut *u* is tightened up. The electric conductor is gripped between the nuts *t* and *u*. The lower 35 end of the said central electrode *a* is made ball-pointed so that any drops of oil which may reach it will tend to drip from the bottom thereof instead of becoming carbonised between the sparking points. The 40 earthed electrode *b* is in the form of a thin thimble, slightly tapered at its lower end and just clearing the inner wall of the base portion *f* so as to be easily removable with the insulator *c*. It is secured in position by 45 being spun or pressed into a small groove *v* in the insulator *c* or instead it may have a small inward protuberance such as a depression made by a punch which protuberance fits into a shallow bayonet groove in the lower 50 part of the insulator *c*. The electrode *b* has internally projecting parts at *x* which form its sparking points and are of proper size to provide the requisite spark gap between them and the central electrode.

55 Referring to Figure 10, in this modification the insulator *c* is made in two parts *c* and *c'*, the latter being added after placing the ring *d* in position. The negative electrode *b* is a rod fitting tightly into a hole in the ring *d*. The cap *k* may be provided with a short laterally extending handle *y* where preferred.

Referring to Figures 11 and 12, a ring *z* 60 below the ring *d* is employed to secure the negative electrode *b*, the latter fitting into a

perforation in a protuberance on the ring *z*, and the insulator being grooved to accommodate the protuberance on the ring and also the part of the rod which projects from the ring. 70

Various modifications may be made in the construction above described, for example, the shape of the sparking points may be varied. Again, the retaining ring *d* may be formed in one with the removable central 75 portion. Such an arrangement is particularly applicable to sparking plugs insulated with mica. Conveniently mica washers are threaded on the lower part of the central electrode, then the metal ring with the external lugs and separated from the central electrode by a number of mica wrappings. There are then more mica washers and the 80 whole is firmly held by the top nut.

Yet again, the cap *k* may be externally 85 screw-threaded and may screw into the base portion *f* or again it may be secured thereto by means of a bayonet or any other appropriate form of joint suitable for this purpose. 90

The removable central portion of the 95 sparking plug consists essentially of the insulator the ring *d* and the two electrodes, *a* *b* and one object of the invention is to render this portion simple, cheap and easy 100 to manufacture. In using the sparking plug, the base portion *f* and the cap *k* do not require to be detached in order to remove the central portion for inspection or repair.

What we claim and desire to secure by 105 Letters Patent of the United States is:—

1. In a sparking plug for an internal combustion engine, a base attachable to the engine cylinder, a removable portion comprising an insulator, electrodes and projecting lugs, a cap adjustably mounted on the 110 said base and having a flange normally engaging the said projecting lugs, the said flange being provided with slots adapted to be brought into register with the said projecting lugs for the purposes specified.

2. In a sparking plug for an internal combustion engine, a base attachable to the engine cylinder, a removable portion comprising an insulator, electrodes and a retaining ring having projecting lugs, a cap adjustably mounted on the said base and having a flange normally engaging the said projecting lugs, the said flange being provided with slots adapted to be brought into 115 register with the said projecting lugs for the purposes specified.

3. In a sparking plug for an internal combustion engine, a base attachable to the engine cylinder, a removable portion comprising an insulator, electrodes, one of which electrodes is ball-pointed and projecting lugs, a cap adjustably mounted on the said base and having a flange normally engaging the said projecting lugs, the said flange be- 120

125

ing provided with slots adapted to be brought into register with the said projecting lugs for the purposes specified.

4. In a sparking plug for an internal combustion engine, a base attachable to the engine cylinder, a removable portion comprising an insulator, electrodes the earthed electrode being fitted to the inner end of the said removable portion and provided with 10 an internally projecting part, and projecting lugs, a cap adjustably mounted on the said base and having a flange normally engaging the said projecting lugs, the said flange being provided with slots adapted to be brought into register with the said projecting lugs for the purposes specified.
5. In a sparking plug for an internal combustion engine, a base attachable to the engine cylinder, a removable portion comprising an insulator, electrodes and projecting 20 lugs, a nut adjustably mounted on the said base and having a part normally engaging the said projecting lugs, the said part being provided with slots adapted to be brought into registration with the said projecting 25 lugs for the purpose specified.

STANLEY FISHER.
WINWOOD PRIDDEY.
